UNITED STATES PATENT OFFICE.

PERCY W. SHAW, OF LYNN, MASSACHUSETTS, ASSIGNOR TO UNITED SHOE MACHINERY COMPANY, OF PATERSON, NEW JERSEY, A CORPORATION OF NEW JERSEY.

THREAD-FASTENING MACHINE.

1,237,711.

Specification of Letters Patent. Patented Aug. 21, 1917.

Application filed May 28, 1914. Serial No. 841,624.

To all whom it may concern:

Be it known that I, PERCY W. SHAW, a citizen of the United States, residing at Lynn, in the county of Essex and State of Massachusetts, have invented certain new and useful Improvements in Thread-Fastening Machines; and I do hereby declare the following to be a full, clear, and exact description of the invention, such as will enable others skilled in the art to which it appertains to make and use the same.

The present invention relates to thread handling machines and more particularly to machines of this type which are employed for temporarily fastening the upper end sole of a lasted shoe together preliminary to the permanent sewing of the inseam.

One object of the present invention is to provide a machine of this type which employs a hooked needle for forming and inserting a thread fastener in the work. With this object in view one feature of the invention contemplates the provision of a hooked needle, means for actuating the needle to pass two loops of thread successively through the work, means for passing one loop of thread through the other, and means for drawing upon the thread from the supply end to lock the loops in the work and set the stitch. The provision of a hooked needle for forming the thread fastening enables a thread to be employed which completely fills the hole in the work and forms a stitch which is locked tightly upon its completion. The utilizing of a hooked needle for forming a stitch also has other mechanical advantages in connection with the operation of the machine which will be obvious to those skilled in the art.

A further object of the invention is to provide a machine for the formation and insertion of a thread fastener which occupies a minimum space lengthwise of the shoe and the insertion of which may be readily and accurately determined by the operator to locate the stitch between the metallic fasteners.

With this object in view a further feature of the invention consists in the combination with a back gage and channel guide for positioning the shoe, of thread fastener forming and inserting devices for inserting a stitch transversely through the upper and insole lip of a lasted shoe. In the simplest and most efficient form of the invention

which has yet been devised, this is accomplished by providing work positioning devices and stitch forming mechanism to which a relative vertical movement is imparted during the formation of a stitch to insert the stitch transversely of the insole lip of a shoe which is held in a substantially horizontal position.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 is a front elevation of a machine embodying the several features of the invention; Fig. 2 is a side elevation of the machine shown in Fig. 1; Fig. 3 is a top plan view of the machine shown in Fig. 1; Fig. 4 is a detail upon an enlarged scale illustrating the construction of the thread cutting mechanism; Figs. 5 to 7, inclusive, are details illustrating the construction of the thread looping and clamping mechanism; Figs. 8 to 11, inclusive, are details illustrating diagrammatically the formation of the thread fastener in the upper and insole lip of a shoe; Figs. 12 to 20, inclusive, are details illustrating diagrammatically the operation of elevating the toe thread from the path of the needle when forming the second stitch for anchoring the toe thread in place; Fig. 21 is a view showing the lasted shoe after the first stitch has been formed for anchoring the toe thread and prior to passing thread about the toe; Fig. 22 is a view illustrating the shoe after the thread has been passed about the toe and prior to the formation of the second fastening; and Fig. 23 is a view illustrating the method of fastening the toe by inserting two anchor fastenings at opposite ends of the toe wire to retain the toe wire in position.

The present machine is intended to insert a plurality of separate unconnected thread fasteners about the sides of a lasted shoe in order to temporarily retain the shoe in its lasted condition and allow the removal of the metallic fastenings prior to the permanent sewing of the inseam. In the present invention this is accomplished by inserting a plurality of vertical stitches transversely

through the upper and insole lip of the lasted shoe between the metallic fasteners, and severing the thread at the completion of the stitch. The thread severing mechanism 5 is under the control of the operator and when passing about the toe may be rendered inoperative in order to bind in the toe by means of a toe thread, as shown clearly in the drawings. It will be obvious to those skilled in the art that when lasting a shoe the metallic fasteners are inserted at the points of greatest strain upon the upper and in order to hold the lasted upper most efficiently it is desirable that the thread fasteners be inserted in as close proximity as possible to these points. The present type of thread fastener may be located as close to the metallic fasteners as desired without liability of the needle of the thread fastening machine encountering the metallic fastener as the relative feeding movement of the work and needle to form the stitch takes place substantially in the direction of the length of the metallic fastener and the thread fastener occupies a minimum space in the direction of the length of the shoe. The present type of fastener is also employed advantageously in anchoring the ends of the toe wire in place when it is desired to retain the toe of the shoe in this manner. As will be observed from an inspection of Fig. 23 of the drawings the fasteners may be inserted across the ends of the toe wire and after the anchor tacks are removed the wire is bent in a reverse direction to lock it in place.

In the illustrated embodiment of the invention the thread fastener consists of two loops of thread passed successively through the lasted upper and lip of the insole by a hooked needle. The use of a hooked needle for the formation of the thread fastener permits a thread to be employed which completely fills the hole in the work, forming a tightly locked fastener which holds the lasted upper securely in place.

A curved hook needle 1 is clamped in a needle segment 3 fulcrumed at 5 and operated from a bell crank indicated at 6, one arm of which is connected to the needle segment through a link 7. The bell crank is fulcrumed upon the machine frame at 8 and is operatively connected with a path cam formed in a cam face 10 and designed to impart two loop forming movements and a thread releasing movement to the needle during each rotation of the cam shaft.

Prior to the engagement of the thread by the needle, the hook 32 is moved along the thread toward the shoe in order to grasp the thread in close proximity to the short end, after which the thread clamp is allowed to clamp the thread in the hook. When the needle has been advanced through the work, the looper is actuated to lay that portion of

the thread between the looper and the thread supply in the barb of the needle, after which the needle is retracted drawing thread from the thread supply to form the first loop. Upon the second passage of the needle through the work, the looper, which is upon the opposite side of the needle, is returned to its initial position to again lay the thread in the barb of the needle for the formation of the second loop. After the second loop has been drawn through the work, the needle is advanced sufficiently to throw the loop out of the barb of the needle, the thread clamp is opened to release the thread and the looper is then moved back to again engage with and clamp the thread between the work and thread supply prior to the severing of the thread. To this end the looper, as a whole, is supported by a cylindrical stud 16 extending through a bearing 17 formed in the machine frame and actuated through an arm 19 extending upwardly from the stud shaft 16 and operatively connected with a path cam formed in the face 20. The end of the shaft 16 is connected with the lower end of a lever 22 fulcrumed upon the machine frame at 24 and having its opposite end actuated by a barrel cam 26. The connection between the lever 22 and the shaft 16, as will be noted from an inspection of Fig. 2, transmits lengthwise movements to the shaft while permitting the shaft to oscillate independently of the lever. With this construction, movements of the looper toward and from the shoe are imparted by rocking the looper and shaft 16 in the bearing 17 and the transverse movements of the looper to lay the thread in the barb of the needle are imparted by a bodily movement of the shaft 16 lengthwise in the bearing. In order to clamp the thread during the formation of a stitch, the looper consists of a sleeve 30 and a hook 32 slidingly supported therein. The hook is actuated to clamp the thread against the lower end of the sleeve by a spring 34 which is interposed between the shoulder formed upon the sleeve and a slide block 36 mounted in a head 37 formed upon the end of the shaft 16. In order to open the clamp against the action of the spring the slide block is provided with a cam roll 38 which engages with the surface of a peripheral cam 40 having a periphery of sufficient width to allow for the necessary transverse movements of the looper. With this construction, the thread is yieldingly clamped by the spring 34 and is positively released at the completion of the stitch by the cam 40 which, as will be seen from the drawings, engages with the cam roll only during the time that the thread clamp is open, thus allowing the looper to rock freely during the formation of a stitch without affecting the operation of the thread clamp.

When the needle is retracted to draw the

130

second loop of thread through the work, it is essential that some means be provided for inclosing the barb of the needle and for casting off the first loop to allow the second loop to be drawn therethrough. To this end a combined needle guide and cast-off is provided which serves not only to support the needle during the piercing of the work but insures that the first loop of thread shall be cast off the needle to cause it to encircle the second loop after it has been drawn through the work. A needle guide 45 is fulcrumed at 5 and is provided with a tooth segment 46 meshing with a corresponding segment 47 formed upon one arm of a bell crank 49, fulcrumed upon the machine frame at 50 and actuated through a peripheral cam 51. The bell crank is permanently maintained in operative relation with the cam by a tension spring 53 connecting the arm of the bell crank with the frame of the machine. During the first advancing movement of the needle, the needle guide is advanced into close proximity with the work to support the needle after which it is retracted to allow the loop of thread to be drawn through the work. Upon advancing the needle a second time, the needle guide is again moved forward into close proximity with the work and remains in this position until the barb of the needle carrying the second loop engages with the needle guide which serves to inclose the thread and prevent the barb of the needle from catching the first loop as the needle is retracted. It will be noted that upon this second advancing movement of the needle, the first loop is thrown out of the barb and the corresponding advancing movement of the needle guide 40 serves to pass it through this loop, thus enabling it to readily cast off the loop when the needle is retracted.

After the thread clamp has released the short end of the thread and prior to its reengagement with the thread, the take-up acts between the thread supply and the work to tighten the first loop and draw the second loop encircled thereby into the work. The thread passes from the thread supply over any suitable form of tension device indicated at 55 and next under guide rollers 57 and 58. A take-up roll 60 engages with the thread between the guide rollers and is journaled upon the lower end of an arm 62 secured to a rock shaft 64. A second arm 65 is also secured to the rock shaft and is operatively connected at its free end with a path cam formed in the face 67 which serves to actuate the take-up in the usual manner to tighten the stitch. The lasted shoe is retained in position during the formation of the thread fastening by a back gage and channel guide arranged to engage with opposite sides of the insole lip and lasted upper. After the shoe has been posi-

tioned properly and upon starting the machine the back gage is actuated to clamp the between substance and hold the shoe during the formation of the thread fastening. After the shoe is clamped in position it is held by the two members during the entire operation of inserting a thread fastening, both the back gage and channel guide being depressed to feed the shoe for the formation of the second loop of thread. At the completion of the thread fastening operation the back gage is automatically retracted to release the shoe. The shoe is positioned in proper relation to the stitch forming mechanism by a channel guide 70 which is adjustably secured to a head 72 and is arranged to project into the channel formed at the base of the insole lip. In order to provide for the feeding of the shoe the head 72 is fulcrumed upon the machine frame at 74 and is operatively connected to a cam path formed in the face 75 through a cam roll 76. With this construction the head 72 is rocked to depress the channel guide and lasted shoe during the formation of the stitch. In order to clamp the shoe against the channel guide a back gage 78 is slidingly mounted in the head and is operatively connected at its rear end with a lever 80 fulcrumed upon the head at 81 and having its upper end operatively connected with a second path cam formed in the face 75 of the cam disk 40 through a cam roll 82. It is desirable that the back gage shall be first moved into engagement with the inseam to position it properly and shall thereafter be forced against the inseam with a yielding pressure to clamp the between-substance firmly during the formation of the stitch. This method of operating the back gage exerts a certain lasting effect upon the upper and the tendency of the parts to spread out to their initial positions when the back gage is retracted insures the formation of a tight stitch in the work. To this end the lower end of the lever 80 is pivotally connected to a rod 83 which slides in a bearing 85 forming a part of the back gage slide 78. The yielding connection between the rod and back gage slide is secured by the provision of a coiled spring 87 interposed between the bearing and lock nuts 88 threaded upon the end of the rod 83. Movement of the rod with relation to the bearing 85 by means of the spring 87 is limited by a stop collar 90 formed upon the rod 83 and arranged to engage with the face of the bearing. With this construction the rod is normally retained with the stop collar in engagement with the face of the bearing and upon advancing the back gage slide the parts maintain the same relative positions until the back gage contacts with the shoe, after which no substantial advance of the back gage takes place and further movements of

the lever 80 serve to compress the spring 87 and yieldingly press the back gage against the shoe. The back gage is locked in its advanced position by a pawl 92 which is allowed to move into engagement at certain predetermined intervals with a ratchet tooth plate 93 secured to the back gage slide. The pawl 92 is mounted upon one end of a lever 94 fulcrumed upon the rocking head 10 at 96 and having a cam roll 97 journaled upon its rear end which is adapted to engage at the proper intervals with a peripheral cam 99. This cam serves to positively unlock the back gage and allow it to be retracted at the proper time, and the spring 101 connecting the arm 94 and locking head serves to normally move the pawl into engagement with the ratchet plate 93. The back gage 78 is removably secured to the back gage slide as indicated at 105 and is provided with a vertical slot 104 to allow the passage of the needle therethrough when forming both loops of thread.

Upon the completion of the thread fastening the thread is severed close to the surface of the work by a knife 106 slidably mounted in the back gage, as shown clearly in Figs. 2 and 4. This knife consists of a thin blade with a cutting edge arranged to coöperate with and shear the thread against the edge of the back gage slot, and pivotally connected at its upper end through a clamp 108 to one arm of a bell crank 110 fulcrumed upon the rocking head at 112. The bell crank normally maintains the knife in a retracted position by means of a spring 113. This retracted position is determined by the engagement of a stop 114 formed upon the second arm of the bell crank and arranged to contact with the side of the back gage. In order to rock the bell crank and impart a cutting stroke to the knife a stud 115 projects from the lower end of the arm 116 and is engaged by the slotted end of a lever 118 pivotally supported at 120 upon a depending arm 122. The arm 122 is pivoted to the machine frame at 123 and is provided with a cam roll 124 which engages with and is actuated by a face cam 125. With this construction the knife is normally maintained in an inoperative position by the spring 113, but at the completion of the thread fastening the cam 125 rocks the bell crank 116 to impart a positive cutting stroke to the knife. It is desirable to provide mechanism under the control of the operator for rendering the cutting mechanism inoperative in order that when desired, two thread fastenings may be connected by a length of thread. To this end, as observed clearly in Figs. 1 and 4, the lever 118 is provided with a slotted end which normally engages with a stud 115, but may be removed from engagement with the stud to break the operative connection by rocking the lever

about the fulcrum 120. To this end the opposite end of the lever is connected to a treadle rod 128 which through the provision of a suitable spring is normally raised to maintain the operative connection between the actuating cam and cutting knife intact. Upon depressing the treadle, however, this connection is broken and the lever 118 oscillated without imparting a corresponding movement to the bell crank. 75

It will be noted that in forming the first loop of thread for the fastening the needle engages with the thread between the thread clamp and supply and that when forming the second loop the needle engages with the thread between the thread clamp and the first loop, there being sufficient slack thread between the thread clamp and material to permit the formation of this second loop. In forming the thread fastening after the toe thread has been laid in place there is no short end and as the thread clamp is manipulated to lay the bight of thread over the barb of the needle this toe thread must be held out of the way in order that it shall not be engaged by the needle and drawn into the work. To this end an auxiliary finger or hook is arranged to engage with the toe thread and remove it from the path of the needle during the formation of the thread fastening. In the illustrated embodiment of the invention this auxiliary finger is normally maintained in an inoperative position but is connected with mechanism under the control of the operator through which it may be actuated at the proper time. A hook 130 is pivotally mounted at 132 upon the end of a lever 133 and is operatively connected with a cam slot 135 through the cam roll 137 in order to oscillate the hook and move it transversely at predetermined intervals. The lever 133 is moved vertically by a stationary cam roll 139 which engages with a curved cam slot 140 formed in the lever. The rear end of the lever 133 is supported by one arm 142 of a bell crank fulcrumed at 143 upon the lower end of an arm 145. The arm 145 is connected with a path cam formed in the face 146 of the cam disk 147 through a second arm 149, as shown clearly in Fig. 3 of the drawings. The bell crank is connected to the arm 149 through a pair of arms 150 and 151 secured respectively to the arms 145 and 149, and a tension spring 152 connecting the ends of the two arms and normally maintaining a tail 153 formed upon the hub of the bell crank in engagement with a lug 154 formed upon the arm 145. With this construction when the arm 149 is rocked by the cam the arms 142 and 145 are moved therewith as a single integral arm to impart a back and forth movement to the lever 133. The lever is retained in an inoperative position by a locking member 155 pivoted 80

75

80

85

100

105

110

115

120

125

130

at 156 and having one end connected with the treadle rod 157 and its opposite end engaging with a shoulder 159 formed upon the rear end of the lever 133. The treadle rod 5 normally retains the locking member in an operative position by any suitable type of spring, not shown, and when the lever is locked in a retracted position the movements of the arm 149 simply rock the arms 10 145 and 151 and expand the spring 152 without moving the lower end of the arm 142 which is pivotally connected to the lever.

The machine is provided with any suitable form of single revolution clutch which 15 serves to start the machine upon a depression of the starting treadle and allows the machine to operate during one complete operation of the cam shaft, after which it is automatically stopped. This mechanism is 20 actuated through a treadle rod 160 connected to the free end of an operating arm 162 which actuates a clutch link 163 having a hook shaped lower end which engages with a pin 165 projecting from the arm 162.

The operation of the present machine is as 25 follows: After the shoe is positioned properly for the insertion of a thread fastening the machine is started and the back gage is actuated to clamp the upper and insole 30 lip against the channel guide. After the shoe is clamped in position the looper 32 is moved along the thread into close proximity to the end and the clamping sleeve is then actuated to tightly lock the thread in the 35 looper. The hooked needle is advanced through the work and the looper is moved transversely to lay the thread in the barb of the needle, as shown in Fig. 8. The needle is then retracted to draw the loop of thread 40 through the work and the back gage and channel guide are depressed, after which the needle is again advanced, bringing the several parts of the machine into the position shown in Fig. 9. With the needle in the 45 position shown in Fig. 9 the looper is returned to its initial position, laying that portion of the thread between the first loop and the looper in the barb of the needle, as shown in Fig. 10. The needle is finally retracted 50 to draw the second loop through the work and during this movement of the needle the needle guide is actuated to protect the barb and cause the first loop to slide over the second, as shown in Fig. 10. The needle and 55 the thread clamp then release the thread and the take-up is actuated to draw upon the supply end of the thread and pull the encircling loop into the work to lock the stitch, as shown in Fig. 11, after which the thread 60 is cut in close proximity to the upper by the thread cutting knife 106. When passing about the toe, as shown clearly in Figs. 21 and 22, the thread cutting mechanism is rendered inoperative, and at the completion 65 of the stitch thread is drawn from the sup-

ply and laid about the toe of the shoe and anchored in place at its opposite end by a second thread fastening. In order to maintain the toe thread in a taut condition during the insertion of the thread fastening it is 70 clamped between the corrugated face of the back gage and the upper after the machine is started, as shown clearly in Fig. 22. During the insertion of this second fastening it is necessary to remove the toe thread from 75 the path of the needle and to this end an auxiliary thread engaging hook is moved into position beneath the thread and is then elevated to hold the thread from the path of the needle during the formation of the 80 stitch, as shown clearly in Figs. 12 to 19, inclusive. In some instances it is desirable to retain the toe wire and lock it at its opposite ends by thread fastenings, in place of the usual anchor tacks. To this end the present 85 thread fastenings are conveniently utilized, as shown clearly in Fig. 23, and the ends of the toe wire bent in a reverse direction to lock it in position. After the requisite number of thread fastenings have been 90 inserted in a lasted shoe all of the metallic fastenings may be removed prior to the permanent sewing of the inseam.

While it is preferred to employ the specific construction and arrangement of parts 95 shown and described, it will be understood that this construction and arrangement is not essential except so far as specified in the claims, and may be changed or modified without departing from the broader features 100 of the invention.

The invention having been described, what is claimed is:

1. A machine for inserting individual unconnected thread fasteners through the upper and insole lip of a lasted shoe, having in combination, a back gage and channel guide for positioning the shoe, and thread fastener forming and inserting devices for inserting a stitch transversely through the 110 upper and insole lip of a lasted shoe.

2. A machine for inserting individual unconnected thread fasteners through the upper and insole lip of a lasted shoe, having in combination, a back gage and channel 115 guide for positioning the shoe, thread fastener forming and inserting devices for inserting a stitch transversely through the upper and insole lip of a lasted shoe, and means for severing a length of thread from the 120 supply.

3. A machine for inserting individual unconnected thread fasteners through the upper and insole lip of a lasted shoe, having in combination, thread fastener forming and 125 inserting devices, and work positioning and clamping devices coöperating during each cycle of operations of the machine to form and insert a thread fastener transversely through the upper and insole lip of the shoe 130

while the shoe is retained against movement in the direction of its length and to release the shoe at the completion of the fastener to allow it to be freely manipulated.

4. A machine for inserting individual unconnected thread fasteners through the upper and insole lip of a lasted shoe, having in combination, a back gage and channel guide for positioning the shoe, stitch forming mechanism including a needle, and means for imparting a relative vertical movement to the stitch forming mechanism and work positioning devices during the formation of a stitch to cause the loops to be spaced vertically from one another in the work.

5. A thread handling machine, having in combination, work positioning devices, a hooked needle, means for actuating the needle to pass two loops of thread successively through the work, means for passing one loop of thread through the other, and means for drawing upon the thread from the supply end to lock the loops in the work to set the stitch.

6. A thread handling machine, having in combination, work positioning devices, means for successively passing two loops of thread through the work and for drawing the second loop through the first in a manner to cause the first loop to encircle the second, and means for pulling upon the supply end of the thread to draw the encircling loop into the work and lock the stitch.

7. A thread handling machine, having in combination, work positioning devices, means for successively passing two loops of thread through the work, means for feeding the work between the formation of the two loops, means for causing the second loop of thread to be drawn through the first in a manner to cause the first loop to encircle the second, and means for pulling upon the supply end of the thread to draw the encircling loop into the work.

8. A thread handling machine, having in combination, work positioning devices, a hooked needle, a looper, mechanism for actuating the needle to pass two loops of thread through the work, and mechanism for actuating the looper transversely of the needle to lay the thread in the barb of the needle for the formation of the first loop and for returning the looper transversely of the needle to its initial position to again lay the thread in the barb of the needle for the formation of the second loop.

9. A thread handling machine, having in combination, work positioning devices, a hooked needle, needle actuating mechanism for causing two loops of thread to be passed through the work, a thread clamp for engaging with the thread adjacent to the end, and mechanism for actuating the thread clamp to lay that portion of the thread between the thread clamp and supply in the

barb of the needle for the formation of the first loop and to next lay that portion of the thread between the first loop and the thread clamp in the barb of the needle for the formation of the second loop.

10. A thread handling machine comprising stich forming mechanism, a thread clamp, means for actuating the clamp to position it adjacent to the end of the thread, and means for causing the clamp to grip the thread during the formation of a stitch and release the thread at the completion of the stitch.

11. A thread handling machine comprising stitch forming mechanism, a hook mechanism for actuating the hook to cause it to engage with the thread, a movable sleeve operatively connected with the hook, and mechanism for actuating the sleeve to cause it to clamp the thread in the hook at predetermined intervals.

12. A thread handling machine comprising stitch forming mechanism, a movable head, a back gage and channel guide supported upon the head and arranged to grip the work between them, and mechanism for actuating the head to impart a vertical movement to the work during the formation of a stitch.

13. A thread handling machine comprising stitch forming mechanism, a movable head, a back gage and channel guide supported upon the head, mechanism for actuating the back gage to grip the work, and means for actuating the head to impart a vertical movement to the back gage and channel guide during the formation of a stitch.

14. A machine for inserting individual and unconnected thread fasteners through the upper and insole lip of a lasted shoe, having in combination, thread fastener forming and inserting devices and thread cutting devices coöperating during each cycle of operations of the machine to form and insert a thread fastener through the upper and insole lip of a lasted shoe and sever the thread, means for rendering the cutting mechanism inoperative to connect two individual fasteners by a loose length of thread when desired, and means for engaging the loose length of thread and removing it from the path of the needle.

15. A thread handling machine, having in combination, stitch forming mechanism including a needle and mechanism for actuating the same, a hook, and mechanism for actuating the hook to engage a loose length of thread between two separated stitches and elevate the thread from the path of the needle on the next advancing movement.

16. A thread handling machine comprising stitch forming mechanism, a hook for engaging a loose length of thread between two stitches, actuating mechanism for the

hook, and means under the control of the operator for throwing the actuating mechanism into operation.

17. A thread handling machine comprising stitch forming mechanism, a hook, and mechanism for actuating the hook to impart a transverse thread engaging movement and a vertical thread elevating movement to the hook.

10 18. A thread handling machine comprising a slotted back gage, a thread cutting knife coöperating with the slot in the back

gage to sever the thread, actuating mechanism for the knife arranged to normally sever the thread at the completion of a stitch 15 comprising a slotted lever, and mechanism under the control of the operator for oscillating the slotted lever and preventing operation of the knife when desired.
